[57]**CLAIM**

The ornamental design for a handle and housing for latch and lock, as shown and described.

DESCRIPTION

FIG. 1 is a front elevational view of a handle and housing for latch and lock showing our new design, with the handle shown in its normal, nested position with respect to the housing;

FIG. 2 is a rear elevational view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a perspective view illustrating principally front, bottom and left side portions thereof;

FIG. 8 is a perspective view illustrating principally rear, top and right side portions thereof; and,

FIG. 9 is a perspective view illustrating principally front and bottom portions thereof, with the view showing the handle extended relative to the housing by being pivoted to an operated position.
